UNITED STATES PATENT OFFICE

2,478,687

HOUSE HEATING BOILER

John B. Detwiler, Mimico, Ontario, Canada

Application April 30, 1945, Serial No. 591,153

3 Claims. (Cl. 122—161)

1

This invention relates to improvements in the vertical type of tubeless boiler particularly adapted for house heating purposes and the principal object of the invention is to materially increase the efficiency of such boilers by effecting a substantial increase in the length of travel of the gases of combustion and the effective area of heat transfer surface contacted by such gases.

A further and important object is to devise a simple construction of boiler which may be fabricated at extremely low cost and which readily lends itself to mass production.

A still further object is to provide a boiler which will operate efficiently with the minimum of care and attention, will be easy to regulate and contains no intricate or delicate parts liable to get out of order.

The principal feature of the invention consists in fabricating a main water jacketed section of steel plate and forming water jacketed extensions spaced from said main section and forming flue passages connected with the combustion chamber of the main section to conduct the gases of combustion in contact with both sides of a substantial portion of said main section and provide an extended active heat transfer passage for such gases for applying heat to the water in said jackets.

A further important feature consists in the provision of a water containing chamber extending across the main water jacketed section intermediate of its height and above the openings connecting the combustion chamber with the extended water jacketed flue passages and providing a damper controlled flue passage therethrough to provide a direct draft, such transverse water chamber being connected with the water jacket of the main section to affect an accelerated water circulation through the boiler.

In the accompanying drawings Figure 1 is a half front elevation and half vertical mid-section of the preferred form of my invention.

Figure 2 is a cross section through the boiler taken on the line 2—2 of Figure 1.

Figure 3 is a small central vertical sectional view through the boiler taken on the line 3—3 of Figure 1.

Figure 4 is a vertical mid-sectional view of a modified form of the invention taken on the line 4—4 of Figure 5.

Figure 5 is a cross sectional view of the boiler shown in Figure 4 taken on the line 5—5 of Figure 4.

Figure 6 is a part plan cross sectional view on a reduced scale taken on the line 6—6 of Figure 4.

2

In the preferred construction illustrated in Figures 1 and 2, the main central water jacketed section is formed of a central steel tube 1 which may be formed of a single steel plate rolled to shape and having the meeting edges secured in a single welded longitudinal joint.

A larger tube 2, also formed of a single rolled steel plate and joined with a longitudinal seam is of a suitable diameter to form a water jacket of desired dimensions.

Suitable ferrules formed of steel plate are fabricated to form frames to connect the inner and outer tubes 1 and 2 around the firedoor opening 3 into the combustion chamber 4, the side flue openings 5 leading out of the combustion chamber and the rear flue opening 6 opening to the combustion chamber and also the clean-out opening 7 spaced above the firedoor opening.

The edges of these ferrules will be welded to the inner and outer tubes 1 and 2 and a rigid structure is thus formed.

The inner tube 1 is formed with a ring of orifices 8 above the flue openings 3 and 5 and they are preferably disposed in a diagonal plane.

Circular plates 9 and 10 are welded in spaced transverse planes above and below the ring of orifices 8 thus forming a water jacketed top to the combustion chamber 4. These plates 9 and 10 are each formed with openings 11 here shown

of oval shape and a ferrule 12 is welded to the said plates to form a flue opening connecting the combustion chamber 4 and the chamber 13 above said plates.

Dished circular crown plates 14 and 15 closing the tops of the tubes 1 and 2 are welded in position and spaced apart to form a top water jacket connected with the jacket between the tubes 1 and 2.

Arranged outside of the outer tube 2 and spaced therefrom is a part cylindrical plate 16 the vertical ends of which are turned inward to meet the outer wall of the tube 2 to which they are welded to form a flue passage 17 which connects with the flue passages 5 leading from the combustion chamber.

Another part cylindrical plate 18 rolled to a larger diameter than the plate 16 is spaced outside the said plate 16 and forms a water jacket 19, the ends thereof being turned inward to meet the outer wall of the outer tube 2 to which they are welded.

The plate 18 extends above the plate 16 and horizontal plates 20 and 21 are cut to fit the outer wall of the tube 2 and are welded to same in vertically spaced relation and to the top edges

of the plates 16 and 18 respectively. Openings 22 are cut in the outer tube 2 to connect the water jacket 19 with the jacket between the tubes 1 and 2.

Vertical baffles 23 and 24 are arranged between the outer side of the tube 2 and the spaced inner plate 16 and are welded in position to extend downwardly from the top plate 20, leaving flue passages 25 at the lower ends.

A circular ring plate 26 is welded to the bottom end of the plate 16 and to the bottom end of the tube 2 which is spaced above the bottom of the tube 1 and a bottom ring plate 27 is welded to the tube 1 and to the outer part cylindrical plate 18, thus forming a water passage between the inner water jacket 2' and the outer part cylindrical jacket 19.

Suitable clean-out opening ferrules 28 are arranged at the bottom of the outer jacket 19 to allow access to the bottom of the flue passage 17 between the inner and outer water jackets.

Suitable return water connections 29 are arranged in the outer plate 18 close to the bottom and a main hot water connection ferrule 30 is arranged in the centre of the upper crown 15.

A main damper controlled outlet flue 31 extends through and is welded to the tubes 1 and 2 close to the crown sheet 14.

A suitable damper 32 is pivotally connected to control the flue opening 11 formed in the inclined water jacketed partition formed between the plates 9 and 10 and is controlled by a damper rod 33 shown extending through the clean-out door opening 7.

It will of course be understood that doors suitably hinged will close the fire door and clean-out door openings.

In the form of the invention illustrated in Figures 4 and 5, plates 34 and 35 for the major portion of their height are formed in U shape, the inner plate 35 being bent at a lesser radius than the outer plate 34 and they are spaced apart a suitable distance to form a water jacket 36 therebetween. The upper portions 37 and 38 of these plates instead of being continued past the transverse diameter at a tangent are bent to form the completion of a cylinder and the abutting ends are welded and these tubular extensions are closed at the top by the crown plates 39 and 40.

The tangential side walls 41 and 42 of the U-shaped portions of the plates 34 and 35 are connected at their vertical ends by plates 43 and 44 spaced apart to form a continuation of the water jacket 36.

Top plates 45 and 46 cut to span the space between the inner and outer plates and to extend between the parallel tangential side walls and the end plates 43 and 44 are welded in place at the lower end of the upper cylindrical portions 37 and 38 and thus continue the water jacket.

In the lower portion of the double walled U-shaped structure thus formed are placed and welded in position the part cylindrical sheets 47 and 48 which thus form a cylindrical combustion chamber 49. The upper ends of the sheets 47 and 48 are spaced below the upper cylindrical portions 37 and 38 to form a flue opening 50.

Spaced-apart bottom sheets 51 and 52 connect the outer vertical part cylindrical sheets 48 and 43, and 47 and 44 respectively and are welded in position.

A spaced-apart pair of part cylindrical sheets 53 and 54 are arranged vertically in mid-position between the sheets 48 and 43 and the bot-

tom ends are connected at a point spaced above the bottom plates 51 by a plate 55 leaving a flue passage 56 thereunder.

The upper ends of the sheets 53 and 54 extend to a point about midway of the height of the flue passage 50 and to the offset upper ends of these sheets are welded the spaced diagonally arranged sheets 57 and 58 which extend to the vertical tangential walls 41 and 42 and project across the combustion chamber and fit and are welded to the inner half cylindrical front wall of the inner U-shaped plate 35.

Water flow openings in the plate 35 connect the water jacket 36 with the space between the sheets 57 and 58.

It will thus be seen that a completely water-jacketed flue is formed leading below the spaced diagonal plates downwardly between and under the cross jacket formed by the plates 53 and 54 and up the outer side thereof and over the top of the paired diagonal plates to an upper chamber 59 from whence the gases of combustion are directed through a flue opening 60.

In both constructions of boiler herein shown and described it will be seen that the gases of combustion rising in the combustion chamber strike a water-jacketed inclined baffle and then flow laterally through side flue passages and are directed first downwardly under the vertical baffles 23 and 24, as shown in Figures 1 and 2 or the water-jacketed vertical baffle formed by the plates 53 and 54 and then re-enter the central chamber above the diagonal baffle before passing out through the discharge flue.

The gases of combustion are thus brought into heat exchange relation with their walled water-jackets over an extremely long passage or passages with the result that a very rapid and continued heat exchange is created to heat and circulate the water entering at the bottom and leaving at the top.

The steel construction readily lends itself to mass production. All the sheets can be pre-cut and shaped ready to be fitted together and welded in sequence and the sheets are so designed that accurate welding can be effected at all joints without difficulty as they are assembled.

There are no intricate or irregularly die-shaped parts requiring great accuracy or precision and the minimum of operations are required to convert the steel plate into a finished product.

It has not been considered necessary to show the details of firing, ash and clean-out doors, grates, dampers, etc., as these are regular accessories to the main boiler structure and can be of varying designs and constructions and do not form part of the present invention.

What I claim as my invention is:

1. A vertical boiler comprising, a substantially cylindrical water jacketed structure having a transverse water jacketed partition intermediate of its height and in communication with the water jacket of said cylindrical structure, flue openings through said cylindrical structure below and above said transverse partition, a flue opening through said water jacketed partition, damper means for closing said last-mentioned opening water jacketed extensions extending laterally from and partly surrounding the cylindrical structure and in communication with the water jacket of said cylindrical structure and spaced therefrom to form flue passages connecting the lower flue openings from the cylindrical structure with the upper flue openings therein, and means interposed in said flue passages for

baffling the gases of combustion in their travel from the lower to the upper flue openings when the flue opening through said water jacketed partition is closed by said damper means.

2. A vertical boiler comprising, a substantially cylindrical water jacketed structure having a flue opening adjacent the top and a transverse water jacketed partition intermediate of its height and forming a combustion chamber in the lower portion, a central opening through said partition and providing direct communication between said flue opening and combustion chamber, damper means closing said central opening flue openings from said combustion chamber, a water jacketed structure arranged outside of and spaced from the outer wall of said combustion chamber and forming water jacketed flue passages, a flue opening communicating with said flue passages and entering said cylindrical structure above said transverse partition to direct gases of combustion from within said combustion chamber through water jacketed paths across the upper surface of said water jacketed partition, said water jacketed structures being in communication to permit free circulation of water therein.

3. A vertical tubeless boiler comprising, a main water jacketed section enclosing a combustion chamber and having a fuel-receiving opening in the wall thereof, a closure for said opening, an inclined water jacketed partition connected with said main water jacketed section and extending across said combustion chamber intermediate of its height to define upper and lower chamber sections, water jacketed extensions connected 30

35

with said main water jacketed section and extending around said main water jacketed section from adjacent one side of said fuel-receiving opening to the other side thereof and forming flue passages opening into said chamber sections and arranged to lead combustion gases passing therethrough from said lower to said upper chamber section over a substantial portion of the outer heat transfer surface of said 10 main section, and a damper controlled by-pass flue arranged in the upper portion of said partition to direct, when open, gases of combustion reflected upwardly by the inclined partition from the combustion chamber directly to said upper 15 chamber section.
